ROAD MACHINE

Carl A. Gustafson, Peoria, Ill., assignor to Caterpillar Tractor Co., San Leandro, Calif., a corporation of California

Application December 7, 1932, Serial No. 646,048

17 Claims. (Cl. 37—156)

The present invention relates to road machines and more particularly to road graders. In the usual type of graders having an earth-engaging tool adapted to be positioned to make a high-angle cut, manually operable adjusting mechanisms are used, which require the provision of compensating mechanism of some description to enable the operator to position the heavy blade assembly in high-angle cutting position. The provision of such compensating mechanism not only entails a complicated lifting mechanism, but also actually decreases the range of operation of such mechanism so that the maximum high-angle cutting position of the blade is unduly limited.

The provision of power-operated control mechanism as disclosed herein does away with the necessity of employing any compensating means, thereby increasing the range of operation of the lifting mechanism and providing a greater maximum high-angle cutting position of the tool. Moreover no effort is required from the operator in making adjustments so that he remains rested and alert to make any needed change of adjustment. Thus the efficiency of the road working apparatus as a whole is increased.

It is an object of the invention to provide a road machine having an earth working tool having a wide range of adjustment and which is controlled easily and positively from the operator's station.

Another object of the invention is to provide a road machine of improved construction and having an earth working tool adapted to be positioned to make a high-angle cut.

Another object of the invention is to provide a road machine having a power control mechanism and a plurality of adjusting mechanisms operable thereby to position an earth working tool to make a high-angle cut.

Another object of the invention is to provide a road machine having an earth engaging tool adapted to be positioned to make a high-angle cut by adjusting mechanisms operated from a source of power.

Another object of the invention is to provide a road machine having power-operated means for adjusting an earth engaging tool from a vertical depending position to an elevated position on either side of the machine.

Another object of the invention is to provide an improved mechanism for locking an earth-engaging tool in its angularly adjusted position with respect to the line of draft.

Another object of the invention is to provide

means for preventing vertical and horizontal play in the tool supporting means of a road machine.

Another object of the invention is to provide a road machine having tilttable wheels and means for limiting tilting movement thereof.

Another object of the invention is to provide an improved draft connection.

Another object of the invention is to provide a power-operated control mechanism having a control element adapted to determine operation of either of two adjusting mechanisms.

Other objects will appear as the description progresses.

- Fig. 32 is a diagrammatic view illustrating a high angle position of the blade with the machine on sloping ground.
- 40 Fig. 33 is a diagrammatic view illustrating a high angle position of the blade with the machine on level ground.

DESCRIPTION OF MACHINE

Frame (Sheets 1, 2, 3, 4, 7, and 15)

The frame of the machine is substantially 45 symmetrical with respect to the longitudinal axis, and includes two side channels 10, 11 (Fig. 2), which extend substantially the length of the machine and have a slight convergence toward the front end. These side channels are interconnected by cross members and braces.

At the front end of the machine, plate 12 is riveted to the forward ends of side channels 10, 11. Angle 13 at the front edge of plate 12 is riveted to plate 12 and to side channels 10, 11. Beneath plate 12 is bracket 14 (Fig. 4) having 55 central horizontal portion 15 provided with bosses 16 welded thereon, and having vertically extending portions 17, 18, which are riveted inside the forward ends of side channels 10, 11, respectively. A framework comprising members 19, 20, 21, 22, 23, 24, is secured to the front end of the frame as a support for a mechanism to adjust the line of draft of which only the parts mounted on the main frame are shown in the drawings.

65 At the rear end of the machine (Figs. 1 and 3), side channels 10, 11 are bent downwardly and rearwardly, and plate 25 is secured to their under sides. The upper edge of plate 25 is reinforced by angle 26. Pairs of angle extensions 27, 28 (Figs. 3 and 10) are secured to the ends of side channels, 10, 11, respectively, by brackets 30, by plates 31, 32, respectively, and by straps 33 (Fig. 3). T-bar 34 has its ends overlapping straps 33, and is secured to the lower edge of plate 25. To the 70 rear ends of extensions 27, 28 is secured angle 35.

Vertical posts 36, 37 (Figs. 10 and 14) are secured to the inner sides of side channels 10, 11, respectively, and serve to support a portion of the blade lifting mechanism. Channel 38 is secured to the lower ends of posts 36, 37, and in addition 5 to reinforcing the framework serves in conjunction with inverted U-bracket 39 (Figs. 3 and 14) to support platform 40. Rear vertical end 41 of engine bracket 42 (Fig. 3) is bolted to channel 38 and the horizontal part thereof extends forwardly through aperture 43 in plate 25 to which forward inclined end 44 thereof is bolted. The ends of U-bracket 39 (Figs. 14 and 15) are secured to plate 45, which together with plates 25, 46 and channel 47 serve as a tool box as well as 10 reinforcing the framework. Plate 46 (Fig. 15) is secured at its edges to inner angles 27, 28, respectively, and to plate 25 at its forward end. Channel 47 is supported on the rear edge of plate 46 and supports the rear edge of plate 45 which is 20 suitably secured thereto. Angles 48, 49 (Figs. 14 and 15) are riveted to the edges of plate 45 and to plates 31, 32, respectively. Plate 45 is secured at its front end to plate 25 in a manner not shown. A framework, consisting of bar 51 (Figs. 1 and 3) 25 secured to post 37, bars 52, 53 (Fig. 10) secured to angle 35 and interconnected by strap 54, supports part of the mechanism for tilting the rear wheels.

In the central portion of the machine above the blade (Figs. 2 and 31), the ends of a pair of 30 spaced apart angles 55, 56 are secured to the top faces of side channels 10, 11 and the connections are reinforced by gussets 57, 58, and angles 59, 60. Angles 55, 56 also serve to support part of the blade lifting mechanism. The ends 35 of a pair of spaced apart angles 61, 62 (Fig. 3) are secured to the bottom faces of side channels 10, 11 beneath angles 55, 56; the central web of T-bar 63 is interposed between angles 61, 62 and is secured thereto. Angles 61, 62, and T-bar 63 40 support the center shift mechanism. The central portion of side channels 10, 11 are further reinforced by angles 64, 65 (Fig. 2) which are secured to the inner lower edges thereof and extend rearwardly to posts 36, 37, to which they are also 45 secured.

Intermediate the front end and the central cross members (Fig. 2) is cross member 66 which is fabricated, having a substantially I-beam cross section and end flanges for securing it to side 50 channels 10, 11. The connections of cross member 66 with the side channels is reinforced by gussets 69, 70.

To obtain rigidity and to prevent weaving, diagonal braces 71, 72, 73, 74, 75, 76, are employed, 55 as shown in Fig. 2. Cross piece 77 is connected to side channels 10, 11, to provide a support for adjusting mechanisms.

Front wheels and tractor pole (Sheets 2, 4, 5 and 6) (100 series numerals) 80

Front wheels 100, 101 (Fig. 4) are journaled on spindles which are integral with bell cranks 102, 103, pivoted at 104, 105, in angles 106 (Fig. 6) which comprise the front axle. Upwardly converging channels 107, 108 (Fig. 4) are secured at their lower ends to angles 106 and at their upper ends to casting 109, having boss 110 (Fig. 9) apertured at 111 and contacting the under side of boss 16 on horizontal portion 15 of frame 70 bracket 14.

Hollow kingbolt 112 passes through aperture 113 and is supported in bosses 16 through which it passes, and at 113, 114 in housing 115 which is provided with flange 116 for attachment to plate

12 of the main frame. Nut 117 is threaded to the lower end of kingbolt 112 and is adapted to be locked thereon by cap screw 118. The front axle and wheels pivot on the vertical axis of the 5 kingbolt.

The front wheels can be tilted with respect to the front axle by rocking bell cranks 102, 103 (Fig. 4) on their pivots 104, 105. For this purpose the upstanding arms 119, 120 of bell cranks 102, 103 are pivotally connected to shift bar 121. Movement of shift bar 121 will impart equiangular oscillations to the bell cranks. To facilitate operation of shift bar 121, a strap 122 is pivotally connected to axle 106 and lug 123 secured to the 15 shift bar.

To operate shift bar 121, sector 124 (Figs. 4 and 6) is secured thereto and meshes with pinion 125 (Fig. 6) on shaft 126 journaled in housing 127 and provided with worm gear 128 (Fig. 4) 20 which is rotated by worm 129 on shaft 130, also journaled in housing 127. Housing 127 has a portion which extends downwardly to fit between angles 106 to which it is secured by bolts. Means are provided for limiting tilting movement of the 25 wheels, said means comprising fingers 124A formed on sector 124 at the ends thereof and adapted to engage said pinion 125 to prevent further movement thereof. The tilting mechanism is operable to impart approximately 30° tilt 30 of the wheels with respect to the frame.

The driving connection for the tilting mechanism includes shaft 131 (Fig. 9) which passes through hollow kingbolt 112 and is operatively connected to worm 129 by an extensible driving 35 connection comprising square shaft 132 telescopically engaging within hollow square sleeve 133. Sleeve 133 has a universal joint 134 with shaft 131, and shaft 132 has a universal joint 135 with worm shaft 130. Rotation of shaft 40 131 effects rotation of worm 129, worm wheel 128, shaft 126, pinion 125, to shift bar 121 to tilt the wheels. The extensible universal connection between shaft 131 and worm 129 enables the shift bar to be operated in all positions of the wheels 45 and axle.

Shaft 131 (Fig. 9) has bevel gear 136 keyed to its upper end and retained thereon. Bevel gear 136 is journaled at 137 in housing 138 which fits the reduced upper end portion of kingbolt 112 50 and is secured thereto by means of lock bolt 139. Bevel gear 136 is driven by bevel pinion 140 keyed to shaft 141 which is journaled at 142 in housing 138 and is provided with sleeve 143 received in housing 138 at 144. Shaft 141 is retained in 55 place in housing 138 by means of nut 145 and fork 146, which is secured to shaft 141 and forms part of universal joint 147, the other fork 148 of which is secured to shaft 149. The rear end of shaft 149 is supported at 150 (Fig. 2) in support 60 71, where it is connected by universal joint 151 to telescopic shaft 152 which is supported on angles 55, 56 (Figs. 2 and 31) at 153 and is driven in a manner to be described hereinafter.

A steerable tractor pole is provided as a draft 65 connection from a tractor to the machine. Pole 155 (Fig. 6) is received at its rear end in cylindrical portion 156 of connection bracket 157 by bolts 158 and lock bolt 159. Bracket 157 is provided with vertical cylindrical portion 161 which receives draft pin 162 (Fig. 9), the lower end of which passes through front angle 106 and is received in apertured bracket 163 secured to said angle. The upper end of draft pin 162 is received 70 in apertured extension 164 of casting 109, being held therein by bolt 165.

At its front end (Fig. 6) pole 155 has housing 166 welded thereto and collar 167 is welded to housing 166. Guide 168 is held in collar 167 by bolts 169 (Fig. 7) which pass through apertures in said collar and engage grooves 170 in said 5 guide 168. Draft bolt 171 extends through central aperture in guide 168 into housing 166. Compression spring 172 surrounds said bolt 171 being held between guide 168 and washer 173 which engages nut 174 on bolt 171. Apertured 10 draft link 175 is pivoted to draft bolt 171. In assembling the above described draft connection, guide 168, spring 172, washer 173 and nut 174 are placed on draft bolt 171 in the order named. This assembly is then placed within housing 166 15 and guide 168 is then positioned so that grooves 170 are aligned with the apertures in collar 167 when bolts 169 are inserted. It is to be noted that either of grooves 170 in guide 168 are adapted to cooperate with either of bolts 169, and that 20 in both positions of said guide a lubricant passage provided therein coincides with the lubricant passage in collar 167.

A pole hanger is provided to relieve the bracket connection of the weight of the tractor pole. 25 Strap 176 (Fig. 6) is pivotally secured at the upper end thereof to the top of braces 20, 22, which comprises a single piece, and is pivotally connected at its lower end to chain 177. Spring 178 is connected to chain 177 and to housing 179 30 30 which is bolted on pole 155 intermediate its ends.

The tractor pole is steerable so that it can be set at an angle with respect to the front axle of the machine so that the machine can be drawn by a traction vehicle which moves along a path 35 parallel to the path of the machine. Connections 180 (Fig. 4) are riveted to front angle 106 adjacent opposite ends thereof and have adjustable rods 181 (Figs. 2 and 6) pivoted thereto. Sprocket chain 182 connects the front ends of 40 rods 181. Said chain 182 engages sprocket wheel 183 (Fig. 8) in housing 179, said sprocket wheel being integral with collar 184 journaled on shaft 185 mounted in said housing 179. By rotating sprocket wheel 183 the length of chain 182 on 45 either side thereof is varied and the angle of the pole with respect to the front axle is varied.

Sprocket wheel 183 is actuated through worm wheel 186 on collar 184, by worm 187 (Figs. 5 and 8) keyed on shaft 188. Said shaft 188 is journaled in housing 179 and carries bevel gear 189 (Fig. 5) which meshes with bevel pinion 190 on shaft 191 journaled in cover 192 of said housing 179. Shaft 191 (Fig. 6) is connected by universal joint 193 to telescopic shaft 194 which has universal joint 195 with shaft 196 journaled in sleeve 197 welded to brackets 198 on strap 176. Shaft 196 has universal connection 199 with telescopic shaft 690 which is driven by the power control mechanism in a manner to be described 55 60 hereinafter.

Rear wheels (Sheets 2, 3, 7, and 8) (200 series numerals)

Rear wheels 200, 201 (Fig. 10) are journaled 65 on spindles integral with bell cranks 202, 203 pivoted at 204, 205 in brackets 206, 207 (Figs. 10 and 14) secured to the ends of I-beam 208. Angles 209, 210 (Fig. 14) are riveted along the lower outside edges of I-beam 208 and are joined at 70 their ends 211, 212, 213, 214, to brackets 206, 207 by welding to provide continuous flanges along the bottom edges of the axle for cooperation with guides 215, 216, 217, 218, on main frame extensions 27, 28.

Rear axle 208 is transversely adjustable with respect to the main frame. For this purpose rack 219 (Fig. 10) is secured to the rear face of I-beam 208 and pinion 220 (Fig. 15) is arranged to mesh therewith. Pinion 220 is operated in unison with worm gear 221. Shaft 222 on which they are secured is journaled in housing 223 which has a depending portion 224 secured to the upstanding web of frame angle 35. Worm gear 221 (Fig. 14) is driven by worm 225. Worm shaft 226 is journaled in housing 223 and has universal joint 227 (Figs. 10 and 14) with telescopic shaft 266, which is operated from the power control mechanism in a manner to be described hereinafter to shift axle 208 transversely of the main frame.

The rear wheels can be tilted with respect to the rear axle. For this purpose the upstanding arms 228, 229 (Fig. 10) of bell cranks 202, 203 are interconnected by shift bar 230 which is guided by strap 231 and shifted by pinion 232 (Fig. 3) and sector 233, the latter being secured to bar 230. Pinion shaft 234 is journaled in housing 235 within which worm gear 236 (Fig. 10) is secured to the shaft. Worm 237 meshes with worm gear 236 and worm shaft 238 is also journaled in housing 235.

Worm shaft 238 has universal joint 239 (Figs. 3 and 10) with telescopic shaft 240, which is operated by the power control mechanism as hereinafter described to tilt the rear wheels. Due to telescopic shaft 240 the wheels can be tilted in any transverse position of the rear axle and wheels.

Means are provided for limiting the tilt of the rear wheels. Fingers 241 (Fig. 10) on sector 233 engage pinion 232 to limit tilt of the rear wheels to the right or left, left hand finger 241 being notched to avoid interference with strap 231 when the wheels are tilted to the left.

Selectively operable control means are provided whereby either the tilting mechanism or the transverse shifting mechanism for the rear wheels may be operated from a single power driven shaft. Shaft 240, which operates the rear wheel tilting mechanism has universal joint 245 (Fig. 10) with stub shaft 246 journaled in boss 247 (Fig. 12) in housing 248 and boss 249 in cover 250 for said housing. Housing 248 is bolted to braces 51, 52, 53 (Figs. 3 and 10). Said shaft 246 (Fig. 12) is provided with three sections of differing diameters. Gear 251 is keyed to the middle portion 252 of said shaft which is threaded to receive nut 235 which holds said gear 251 against the shoulder formed by larger portion 254 of said shaft 246. Gear 251 engages boss 247 in housing 248 and with spacer 255 and nut 253 serves to locate said shaft 246 in said housing. Seal 257 is seated in boss 247 and engages shaft 246. Shaft 261, similar to shaft 246, is similarly mounted in housing 248 and cover 250 therefor, and has gear 262 keyed thereon and fixed with respect thereto by nut 263. Seal 264 is seated in the boss in housing 248 and engages shaft 261. Said shaft 261 (Fig. 10) has universal joint 265 with shaft 266 which operates the transverse shifting mechanism for the rear wheels and axle.

Gears 251 and 262 are offset from each other and a third gear is provided which is shiftable manually to transmit a power drive to either of said gears 251, 262. Gear 270 is slidably and non-rotatably mounted on splined shaft 271, lower reduced end 272 of which is journaled in boss 273 of housing 248. Said shaft 271 is journaled at its top in boss 274 in cover 250, said

boss also engaging the bottom of bevel gear 275 integral with said shaft 271. Gear 270 is provided with grooved hub 276 (Figs. 12 and 13) which is engaged by pin 277 (Fig. 13) on crank 278 of shaft 279. Said shaft 279 is journaled in boss 280 of housing 248, and seal 281 is seated in said boss and engages said shaft. Lever 282 pinned on shaft 279 is provided on its shorter arm with cup 283 in which spring 284 is compressed between plug 285 and ball 286. Ball 286 is adapted to engage either of a pair of depressions in boss 287 on housing 248.

Lever 282 is movable to either of two positions to engage gear 270 with either of gears 251, 262, spring-pressed ball 287 serving to retain said lever 282 and said gear 270 in adjusted position. In this manner shaft 271 and gear 270 are adapted to operate the tilting mechanism for the rear wheels or the lateral shifting mechanism for the rear wheels and axle.

The power drive is transmitted to shaft 271 and gear 270 by bevel pinion 290 (Fig. 3) which meshes with said bevel gear 275. Pinion 290 is keyed on shaft 291 journaled in housing 292 mounted on said cover 250. The reduced forward end of shaft 291 has a driving connection with sleeve 293 which is driven from the power control mechanism in a manner to be herein-after described. Sleeve 293 is housed in shield 294, the rear end of which is held in housing 292 by lock bolt 295 (Figs. 2 and 3). The forward support for said shield is described hereinafter.

Blade and circle (Sheets 1, 6, 9, 10 and 11) (300 series numerals)

Blade 300 (Fig. 16) consists of cutting edges 301 secured to moldboard 302 and end bits 303, 304 secured to moldboard 302 and overlapping said cutting edges 301. Angle bracket 305 (Fig. 20) is secured to moldboard 302 and angle 306 is secured to the trailing edge of angle 305. Brackets 307, 308, 309, 310 (Figs. 2 and 17) are secured to angle bracket 305. Corresponding brackets 311, 312, 313, 314 are secured to moldboard 302. Brackets 307—314 are used for connecting the blade to the circle assembly in different positions.

Circle 315 (Fig. 17) is made of a single piece of angle bent into a circle with the ends joined by welding. Beam 317 has a central portion 318 which is bent into a semi-circle of substantially the same radius as the circle. This central semi-circular portion of the beam encompasses approximately one-half of the circle and is riveted thereto. End portions 319, 320 of beam 317 extend tangentially from the circle and downwardly, their lower ends being apertured for connection to the brackets on angle 305 by means of pins 323, 324. In order to rigidly connect the ends of the beam to the circle, brackets 325, 326 (Fig. 16) are riveted to end portions 319, 320. The upper ends of brackets 325, 326 are riveted to the ends of channel 327 which is rigidly connected to circle 315 by brackets 328, 329 (Fig. 17). In addition, the lower ends of brackets 325, 326 are rigidly secured by gussets 330, 331 (Fig. 16) to the lower ends of inclined braces 332, 333, the inner ends of which are riveted to channel 327.

The blade 300 is angularly adjustable about the axis of pins 323, 324 (Fig. 20) to alter the inclination of cutting edges 301 to the surface of the ground. To lock the blade in adjusted position, links 334, 335 (Fig. 17) are connected by pins 336, 337 to the brackets on the moldboard.

- The inner faces of links 334, 335 are serrated to engage with corresponding serrations in clamping blocks 340, 341 on the beam. A plurality of brackets 307 to 314 is provided so that the 5 blade may be connected to the beam in different transverse positions with respect to the surface so that the blade can be made to extend farther outwardly to the left or right of the machine as desired.
- 10 The circle is revolvably mounted in a framework (Fig. 17) consisting of forwardly converging side bars 342, 343 and rear cross bar 344. The rear end of side bar 342 is rigidly connected with the left end of bar 344 by bracket 345 to the 15 webs 346, 347 of which they are bolted. Similarly the rear end of side bar 343 is rigidly connected with the right end of bar 344 by bracket 348. The front ends of the side bars are secured to a hollow connection block 349 (Fig. 20) 20 in which is pin 350 for a purpose hereinafter described. The intermediate portions of the side bars are rigidly connected together by casting 351 (Fig. 17).
- 25 The inwardly extending flange of the circle rests on an arcuate ledge 352 (Fig. 22) which is formed integrally with bracket 345, and above the rear end of ledge 352 a portion of the bracket is extended over the inwardly projecting flange of the circle where it is provided with a boss 353 30 (Fig. 17) adapted to receive a rub iron having adjusting screw 354. The rub iron may be of the type disclosed in my Patent No. 1,698,435, dated January 8, 1929. Adjustable shoe 355 (Figs. 21 and 22) is supported in bracket 345 by bolts 356 which engage elongated slots formed in said shoe and are provided with washers 357. Said shoe 355 engages the inner edge of the horizontal flange of circle 315 and is provided with inward extensions 358 which are engaged by adjusting 35 screws 359 threaded in a flange of bracket 345 and having lock nuts 360. Thus shoe 355 is adjustable radially to prevent play between the circle and its support. The arcuate ledge provides a support for the circle on which the circle can 40 be revolved and the adjustable shoe and the rub iron serve to take up wear in the parts and to reduce the amount of play between the circle and the support. Bracket 348 is similarly equipped. Likewise, a ledge 361 (Figs. 17 and 19) 45 is provided under the front right corner of casting 351 to support circle 315 and an adjustable rub iron in boss 362 is associated therewith. The casting is similarly constructed at the left front corner. Thus, four arcuate ledges, arranged in 50 a circle, are provided on the circle supporting framework which permit the circle to be revolved thereon, and there are adjustable means associated therewith to take up play both vertically and horizontally.
- 55 The circle supporting framework is connected by drawbars 370, 371 (Fig. 17) to the front end of the main frame (Fig. 1) where bosses 16 (Fig. 9) on U-bracket 14 have rearward extensions forming fork 372. Drawbars 370, 371 (Fig. 17) converge forwardly to a connection 373 to which they are bolted. In connection 373 is a bolt 374 having an apertured head 375 which is connected by pin 376 to fork 372 (Figs. 1 and 9). Bolt 374 can swing in a horizontal plane about the vertical axis of pin 376, and, due to the rounded edges of the aperture in the head 375 and the wide spacing of the jaws of fork 372, bolt 374 is capable of a limited oscillation in the vertical plane, as well. The rear end of drawbar 371 is pivotally 60 connected to the circle supporting framework at 75
- 377 (Fig. 17) and the rear end of drawbar 370 is pivotally connected thereto at 378. By reason of these pivotal connections between the drawbars and the circle supporting framework, the framework, together with the circle and the blade, can be raised and lowered with respect to the drawbars, or, in other words, the angle between the drawbars and the plane of the circle can be varied. Also, the drawbars, together with the circle and blade assembly, as a unit, are capable 10 of a limited universal movement about the intersection of the axes of pin 376 and bolt 374 as a center.
- 15 To summarize the movements of adjustment of which the circle is capable, they are, an arcuate movement in a horizontal plane about the vertical axis of pin 376; an arcuate movement in vertical planes containing the axis of pin 376, oscillation about the axis of bolt 374; a jackknife movement between the circle and the drawbars; and oscillation of the circle about its center. The desired circle adjustment is usually obtained by combination of these movements.
- 20 *Blade lift (Sheets 2, 3, 7, 9, 15 and 16) (400 series numerals)*
- 25 The ends of rear cross bar 344 (Fig. 16) of the circle supporting framework are connected by ball and socket joints 400, 401 to links 402, 403 which telescope in links 404, 405 which are connected by ball and socket joints 406, 407 to lift arms 408, 409, secured to the forward ends of shafts 410, 411. Links 402, 404 and 403, 405 are provided with spaced apertures to receive pins 412, 413 by means of which the telescoping links 30 can be secured together at the desired length. In addition, link 404 can be secured to link 402 by clamp 414, and link 405 can be secured to link 403 by clamp 415. The link connections between the ends of bar 344 and lift arms 408, 409 are 35 adapted to be adjusted at different lengths for a purpose hereinafter described. The forward ends of shafts 410, 411 are supported in bearing brackets 416, 417 which are supported from the main frame by means of portions integral therewith 40 which extend inwardly between the upstanding flanges of angles 55, 56 (Fig. 31) and which are riveted thereto. The rear ends of shafts 410, 411 45 (Fig. 10) are supported in bearings in housings 418, 419 which are secured to posts 37, 36. The rear end of shaft 410 has worm gear 420 secured thereto within housing 418, and worm gear 420 is adapted to be driven by worm 421 on worm shaft 422 which is journaled in housing 418 (Fig. 11). Worm shaft 422 extends inwardly from housing 50 418 and is also journaled in housing 424 which is supported in housing 418 at 425, being clamped therein. Bevel gear 426 is keyed on worm shaft 422 and engages bevel pinion 427 on shaft 428 which is journaled in bushings 429, 430 in cover 431 for housing 424. Bushing 430 extends forwardly from housing 424 and cover 431 and is mounted in clamp bracket 432 bolted on angle 64 which serves to brace said housing 424. The forward end 433 of shaft 428 is square and has 55 telescopic engagement with hollow square shaft 434 which is driven by the power control mechanism in a manner hereinafter described. Thus it is seen that upon rotation of worm 421, worm wheel 420 and shaft 410, lift arm 408 is oscillated 60 to raise or lower lift links 402, 404 to correspondingly adjust the left end of the blade.
- 65 The right end of the blade (Fig. 16) is adjustable similarly by lift links 403, 405, arm 409, shaft 411, and a worm wheel and worm in housing 419 70

similar to worm wheel 420 and worm 421. Housing 436 (Figs. 2 and 3) contains gearing similar to bevel gear 426 and bevel pinion 427 which serves to transmit the drive to the worm and worm wheel in housing 419, and which are driven by telescopic shafts including hollow square shaft 437 (Fig. 3) similar to shaft 434. The round forward end of shaft 437 is journaled in housing 438 which is secured to angles 60, 65 (Fig. 31). Spur gear 439 (Fig. 3) on shaft 437 engages spur gear 440 on shaft 441 also journaled in housing 438. Shaft 441 has universal joint 442 (Figs. 3 and 31) with telescopic shaft 443 which is driven by the power control mechanism in a manner to be hereinafter described.

The forward end of hollow square shaft 434 is journaled in housing 446 (Fig. 31) secured to angles 59, 60 and having gearing similar to spur gears 439, 440 in said housing 438. Said shaft 434 and the gearing in housing 446 are driven through universal connection 447 and telescopic shaft 448 by the power control mechanism in a manner to be hereinafter described.

It is seen, therefore, that rotation of telescopic shafts 443, 448 serves to raise or lower the respective ends of bar 344 of the blade and circle assembly whereby the blade is correspondingly adjusted.

By reason of the fact that shafts 410, 411, at the points at which arms 408, 409 are connected thereto extend outside the main frame (Fig. 33), each of the arms 408, 409 is capable of assuming a substantially vertically depending position and has a range of movement of approximately 270°. Due to the fact that the links 402, 404 and 403, 405 are adjustable, the angle of inclination of the circle and blade to the wheels-ground-contacting plane A—A can be further increased. As shown in Fig. 33, the cutting edge can be positioned so that the surface of the ground after it is cut is substantially 62° to the axis of the adjacent wheel. The blade can also be adjusted to the same angle of inclination on the other side of the machine, and to permit this adjustment, links 403, 405 are extended and links 402, 404 are shortened. The blade can be adjusted to any angle of inclination with respect to plane A—A within these limits of extreme inclination at each side.

50 Circle shift (Sheets 2, 3, 7, 9-12, and 16) (500 series numerals)

Means are provided for (1) shifting the center of the circle transversely of the machine or about the center of pin 376; (2) shifting the circle on its own center, and (3) adjusting the plane of the circle with respect to the drawbars.

(1) For shifting the center of the circle, the supporting frame of the circle is adapted to be variously connected by a link to a rack on the main frame which can be slid transversely of the main frame. Rear cross bar 344 (Fig. 16) of the circle supporting framework is provided with apertures 500, 501 adjacent its ends for connection to a link 502 having a hooked end for connection with apertured lugs 503, 504, 505, depending from rack 506 which has channels 507, 508 (Fig. 3) formed integrally therewith for engagement with the flanges of T-bar 63, which, as explained before, is secured to the main frame. Rack 506 is adapted to slide along bar 63 and for this purpose is engaged with pinion 509 (Fig. 25) on shaft 510 journaled in housing 511 mounted on angles 61, 62. Keyed to shaft 510 within housing 511 (Fig. 26) is worm gear 512 which is driven by

worm 513 on hollow shaft 514, also journaled in housing 511.

Integral clutch element 515, on the rear end of hollow shaft 514, is adapted to cooperate with clutch element 516 formed within sleeve 517 at the forward end thereof. Said sleeve 517 is slidably mounted in housing 518 which extends within and is secured to housing 511. Sleeve 517 is rotated by means hereinafter described and is shiftable in the direction of arrow 519 to engage clutch elements 516, 515, whereby a drive is transmitted to worm 513, worm wheel 512, and pinion 509 to shift rack 506 in either direction. Rack 506 (Fig. 16) through link 502 serves to shift the blade and circle assembly transversely with respect to the main frame.

To shift sleeve 517, said sleeve is provided with peripheral rack 521 (Fig. 24) which is engaged by pinion 522 integral with shaft 523. Shaft 523 (Fig. 25) is journaled in boss 524 of housing 518 and lever 526 is pinned thereto. Lever 526 is pivotally connected at one end to rod 527 (Figs. 3 and 25) which extends rearwardly to the operator's station where it is supported in bracket 528 (Fig. 10) secured to control clutch housing 527 and is provided with handle 529. Thus it is seen that handle 529 controls clutching mechanism adapted to establish a driving connection to the center shift mechanism.

Means are provided to maintain handle 529 and the associated clutch mechanism resiliently in adjusted position. The shorter arm of lever 528 (Fig. 25) is formed with cup 531 forming a seat for spring 532 which urges ball 533 into engagement with seats formed in boss 534 of housing 518 (Figs. 3 and 25).

For normal operation, the center shift mechanism is adjusted as illustrated in Fig. 16 with link 502 engaged with the central apertured lug 504 on rack 506, and with the other end of link 502 engaged with either aperture 500 or aperture 501 in bar 344 depending on the angular adjustment of the circle itself; that is, depending on the angle of the cutting edge with respect to the longitudinal axis of the machine. The center shift mechanism can be operated to shift rack 506 toward either side of the machine, thereby shifting the center of the circle to extend the blade farther out on either side. By engaging link 502 with lugs 503 or 505, the range of center shift can be further increased, so that a plurality of ranges of center shift are obtained with a single rack. This arrangement is necessary (Fig. 32) to shift the center of the circle well to one side of the machine to obtain extreme angles of inclination of the blade. With the wheels tilted, as illustrated by Fig. 32, the blade can be inclined at approximately 82° to the axis of the rear wheel; and almost the entire blade assembly is outside the vertical plane of the side of the frame, as indicated by the line Y—Y. The lift links alone could not maintain the blade and circle in this position because of their pivotal connection with the circle supporting frame and the lift arms; but, by the addition of the center shift link connection, the chain of linkage comprising the main frame, link 403, 405, link 344 (with which the circle and blade are a unit), link 402, 404, and link 502, is a locked kinematic chain. Link 402, 404 is pivoted to the frame at 406; link 403, 405 is pivoted to the frame at 407; link 502 is pivoted to the frame at 505. Link 402, 404 is pivoted at 400 to link 344 and adjacent that end, link 344 is pivoted to the end of link 502 at 500; the other end of link 344 is

pivoted to the end of link 403, 405 at 401. In the extreme limit of movement link 502 is substantially parallel to link 344. Fig. 33 shows a high-angle position of the blade obtained by using shorter center link 502A.

(2) For shifting the circle on its center, it is provided with an arcuate rack 536 (Fig. 20) secured underneath the inwardly extending flange of said circle 315. A pinion 537 engages rack 536. Pinion 537 is keyed in the lower end of shaft 538 which is journaled in housing 539 which extends through and which is secured to casting 351. Within housing 539 worm gear 540 (Figs. 20 and 23) is secured to the upper end 15 of shaft 538 and engages with worm 541 (Fig. 23) on worm shaft 542 journaled in housing 539. Shaft 542 (Fig. 20) is connected by universal joint 543 to square shaft 544 which telescopes in hollow square shaft 545, the upper end of 20 which is connected by universal joint 546 (Fig. 16) to shaft 547 (Fig. 24) which passes through hollow shaft 514. The rear end of shaft 547 has a clutch element 548 formed thereon which is adapted to be engaged by said clutch element 25 516 of sleeve 517. Clutch members 516, 548 are engaged for operating shaft 547 by sliding sleeve 517 in the direction of arrow 549 in Fig. 24. When so engaged, rotation of sleeve 517 will result in rotation of pinion 537 (Fig. 20) causing 30 rotation of circle 315 about its center. This adjustment is made to vary the angle of the cutting edge with respect to the longitudinal axis of the circle supporting frame, or, in other words, with respect to the line of draft. By reason of 35 the telescopic connection between shaft 544, 545, and the universal joints 543, 546, the circle can be adjusted in any position of the circle supporting frame.

Sleeve 517 as operated by lever 526, rod 527, 40 and handle 529 comprises a selectively operable control for obtaining two adjustments of the circle; it can be pushed forwardly to enable the drive train for shifting the center of the circle, and pulled rearwardly to enable the drive train 45 for shifting the circle on its own center.

Sleeve 517 is rotated selectively in either direction from the power control mechanism. Said sleeve 517 is provided with internal splines (Figs. 24 and 25) which engage pinion 550 integral with 50 stub shaft 551 (Fig. 24) which is journaled in housing 518 at one end and in bushing 552 in the recessed end of shaft 547 at its other end. Shaft 551 has universal joint 553 (Fig. 2) with telescopic shaft 554 (Fig. 2) which is operated 55 from the power control mechanism in a manner hereinafter described.

The circle is adapted to be locked in adjusted position with respect to its supporting frame. For this purpose, the inwardly extending flange 60 of circle 315 is provided with a series of notches 555 (Fig. 17) with which a locking pin 556 (Figs. 18 and 19) is adapted to be engaged. Locking pin 556 is supported in three aligned apertures 557 in casting 351 and is adapted to be slid up 65 and down therein. As the circle is shifted, the notches 555 are successively brought into alignment with apertures 557 and in the locking position locking pin 556 is lowered into engagement with one of the notches 555, thereby locking the 70 circle with respect to the circle supporting frame. Bracket 558 is secured to casting 351 and a pair of integral spaced arms 559 are pivoted in said bracket at 560. Pin 561 having its ends secured to arms 559 underlies lever 562 which is pivoted 75 at 563 in lugs 564 on bracket 558. The nose of

lever 562 engages with slot 565 in locking pin 556 (Figs. 18 and 19). By rocking arms 559 clockwise, pin 561 permits the nose of lever 562 to seat pin 556 in notch 555, lever 562 being urged into the locking position by spring 566. The upper end of spring 566 is seated in bracket 558, and the lower end of spring 566 bears against a washer which is retained by nut 567 on bolt 568 which passes through an aperture in lever 562. Locking pin 556 is automatically retained 10 in its raised position against the urge of spring 566 by a ridge 569 on the under side of lever 562 which contacts pin 561. Arms 559 are operated by rod 570, and the end of web 571 on lever 562 acts as a limit stop against which pin 561 15 strikes when rod 570 is pulled to raise the locking pin. This end 571 is also designed to strike hub 559' of arms 559, to limit the downward movement of locking pin 556. Rod 570 (Fig. 17) extends forwardly through an aperture in 20 bracket 582 which forms a guide therefor. Rod 572 (Fig. 20) is pivoted in the ears of bent lug 573 welded to rod 570. Said rod 572 extends upwardly and rearwardly to the operator's station and is supported in bracket 574 (Fig. 10) 25 secured to control clutch housing 627. The rear end of said rod 572 is formed as a handle 575 which the operator grasps to operate the circle lock.

(3) For adjusting the plane of the circle with respect to the drawbars, there is provided a screw 576 (Fig. 20) the lower end of which is provided with an eye 577 through which pin 350 passes. Screw 576 is threaded through hub 578 of bevel gear 579 and passes through apertures 580, 581 in bracket 582 which is secured to drawbars 370, 371 (Fig. 17). Bracket 582 restrains axial movement of bevel gear 579 and its hub 578 so that rotation thereof serves to feed screw 576 axially. A plate 583 (Fig. 20) is 40 secured to bracket 582 and extends downwardly between the forward ends of side bars 342, 343 as a guide therefor and is provided with lugs 584 which serve as a limit stop. Bracket 582 is provided with an apertured boss 585 to support 45 stub shaft 586. Bevel pinion 587 is secured at the forward end of stub shaft 586 and meshes with bevel gear 579. The rear end of shaft 586 is connected by universal joint 588 to square shaft 589 which telescopes within hollow square 50 shaft 590 (Fig. 2). The rear end of shaft 590 is connected by universal joint 591 to the front end of shaft 592 which is supported in bracket 593 having a depending portion interposed between angles 55, 56 of the main frame and secured thereto. Shaft 592 is operated from the power control mechanism in a manner herein-after described. When shaft 592 is rotated, it serves to rotate bevel gear 579 (Fig. 20) and collar 578 to project or retract screw 576 thereby adjusting the angle of the circle with respect to the drawbars. Due to the telescopic connection between shafts 589 and 590 and universal joints 588 and 591, this adjustment can be made 55 in any position of the circle or drawbars. 65

*Power control (Sheets 1, 2, 3, 7, 9, 13, 14 and 15)
(600 series numerals)*

The power control mechanism disclosed herein 70 comprises reversible clutching mechanism which is powered by a motor and which is controllable by the operator to drive the adjusting mechanisms for the machine.

Motor 600 (Figs. 3 and 10) is bolted to motor support 42 and is located at the front of the 75

operator's station below the control clutch housing. Sheaves 601 (Fig. 3) are driven by motor 600 and are connected by belts 602 with sheaves 603 on shaft 604 (Figs. 29 and 30). Shaft 604 (Fig. 29) is mounted in bearing 606 in housing 607, oil seal 608 being seated in said housing and engaging said shaft. The rear end of shaft 604 is mounted in bearing 609 in said housing 607, nut 611 being threaded on said shaft. Housing 607 is supported from housing 612 by cap screws 613.

Worm 614 (Fig. 30) on shaft 604 engages and drives worm wheel 616 keyed to the lower end of vertical shaft 617 and held thereon by nut 618 (Fig. 29). Said shaft 617 is journaled adjacent its lower end in bushing 619 in housing 612 and has bevel gear 621 keyed to its upper end. Hub 622 of gear 621 is journaled in bushing 623 in housing 612. Collar 624 of said bushing 623 engages said bevel gear 621 and circular boss 626 of housing 612. Housing 612 is supported from control clutch housing 627 by cap screws 628.

Said bevel gear 621 is positioned within said housing 627 and meshes with opposite bevel gears 629, 631 journaled on bushings on shaft 632. Shaft 632 is journaled in bushings in boss 633 of housing 627 and in boss 634 of cover 636, which is secured to housing 627 by cap screws 637 (Fig. 27). Seal 638 is seated in boss 633 and engages shaft 632. Spacers 639 are placed on shaft 632 between central splined portion 641 of said shaft and bevel gears 629, 631 and the bushings on which said gears are journaled.

Hubs 642, 643 of bevel gears 629, 631, respectively, are formed with beveled clutch teeth adapted to cooperate with complementary beveled clutch teeth of double-faced clutch element 644, slidably and non-rotatably engaged with splined portion 641 of shaft 632.

Clutch element 644 is shiftable in either direction to transmit a drive from either of oppositely rotating gears 629, 631 to shaft 632. Peripheral groove 646 in clutch element 644 is engaged by fork 647 pinned on shaft 648. Shaft 648 is slidably mounted in boss 649 in housing 627 and boss 651 in cover 636 through which it extends. The rear end of shaft 648 is pivoted at 652 to control lever 653 intermediate its ends. Lower 50 rounded end 654 of lever 653 has a floating, pivotal mounting in apertured boss 656 on cover 636.

Thus it is seen that clutch element 644, shaft 648, and control lever 653 have a central neutral position and two active positions which serve to transmit opposite drives to shaft 632. Resilient means are provided for retaining these parts in their neutral position. At its forward end shaft 648 is provided with peripheral groove 657 engaged by ball 658 in the neutral position of said shaft under the influence of spring 659, seated in an upward extension of said boss 649 against plug 660. As the horizontal aperture in boss 649 is closed, the end of shaft 648 engaged therein is flattened to permit passage of air during movement of said shaft.

Thus a reversible clutch mechanism is provided to transmit a power drive to a control shaft, manual control means being provided which is maintained resiliently in neutral position, and 70 which is returned automatically to neutral position by the camming action of the beveled clutch teeth upon manual release of the control means or when an abnormal resistance of the adjusting mechanism operated thereby occurs, as when 75 some obstruction is encountered.

Housing 627 (Fig. 27) is secured to side channels 10, 11 and posts 36, 37, respectively, by brackets 661, 662.

To the left of shaft 632 as viewed in Fig. 27, similar shaft 663, 664 are similarly mounted in housing 627 and cover 636, and to the right thereof similar shafts 665, 666, 667 are similarly mounted in housing 627 and cover 636. Shaft 668, to the right of shaft 667, is similar to shaft 632 but differs therefrom in certain particulars 10 hereinafter noted. Two opposite trains of intermeshing spur gears are rotatably mounted on said shafts, all of said spur gears being similar with the exception of spur gears 669, 670 integral with bevel gears 629, 631, respectively, on shaft 15 632, which serve to drive said trains constantly. Said trains of gears form part of a series of similar reversible clutch mechanisms and only one will be described in detail.

Adjacent the right end of housing 627 spur 20 gears 671, 672 journaled on bushings on shaft 668 have hubs 673, 674 formed with beveled clutch teeth adapted to cooperate with complementary beveled clutch teeth of double-faced clutch element 675 slidably and non-rotatably 25 mounted on splined portion 676 of shaft 668. Spacers 677 are mounted on shaft 668 between said splined portion 676 and spur gears 671, 672, respectively. Movement of clutch element 675 to transmit a drive to shaft 668 from either of 30 gears 671, 672 is controlled by fork 678, shaft 679 (Fig. 28) and control lever 680, similar to fork 647 (Fig. 29), shaft 648, and control lever 653 heretofore described, and similarly mounted.

Similar reversible clutch mechanisms are as- 35 sociated with each of shafts 663, 664, 665, 666, 667 (Fig. 27) and are controlled by similar mechanism including control levers 681, 682, 683, 684, 685, respectively, (Figs. 27 and 31).

Each of said shafts is adapted to operate an 40 adjusting mechanism heretofore described. Shaft 663 (Fig. 27) extends through the front of housing 627 and is connected by universal joint 686 (Figs. 2 and 31) with telescopic shaft 452 which is adapted to operate the tilting mechanism for 45 the front wheels as described heretofore.

Shaft 664 (Fig. 27) extends through the front of housing 627 and is connected by universal joint 687 (Figs. 2 and 31) with telescopic shaft 448, which operates the lift mechanism for the left 50 side of the blade and circle assembly as heretofore described.

Shaft 662 (Fig. 27) extends through the front of housing 627 and is connected by universal joint 688 (Figs. 2 and 31) with telescopic shaft 534 55 which operates either the center shift mechanism or the mechanism for shifting the circle on its center as heretofore described.

Shaft 665 (Fig. 27) extends through the front of housing 627 and is connected by universal joint 689 with telescopic shaft 690 (Figs. 1 and 31) journaled in bracket 691 (Fig. 1) on cross-piece 77 and connected by universal joint 198 to shaft 196 which operates the mechanism for adjusting the angle of the tractor pole with respect 65 to the front axle, as heretofore described.

Shaft 666 (Fig. 27) extends through the front of housing 627 and is connected by universal joint 693 (Figs. 2 and 31) with shaft 592 which operates the mechanism for adjusting the angle 70 of the drawbars with respect to the circle as described heretofore.

Shaft 667 (Fig. 27) extends through the front of housing 627 and is connected by universal joint 694 (Figs. 2 and 31) to telescopic shaft 443 75.

which operates the lift mechanism for the right side of the blade and circle assembly as heretofore described.

Shaft 668 (Fig. 27) is journaled in bushings in 5 boss 695 in housing 627 and boss 696 in cover 638 and has gear 697 keyed to the front end thereof. Gear 697 meshes with gear 698 keyed on shaft 699 journaled in bushings in bosses 700, 701 of housing 627. Shaft 699 is located above and 10 to the right of shaft 668. Reduced square end 702 of shaft 699 is received within hollow square shaft 293 housed in shield 294 as described heretofore. Shield 294 is supported at its forward end in housing 627. Shaft 293 operates either the 15 tilting mechanism for the rear wheels, or the mechanism for shifting the rear wheels and axle laterally, as heretofore described.

In the foregoing description a plurality of adjusting mechanisms have been described, each 20 one of which is adapted to effect an adjustment of the blade to vary its cutting position. All such adjusting mechanisms which require the outlay of considerable force are operated by power from the power control mechanism. The combined 25 effect of all these adjusting mechanisms is utilized in positioning the blade to make a high-angle cut, one of such positions being illustrated in Fig. 32. In said figure, the blade is connected in its furthest right position with respect to the circle as viewed by the operator, link 502 is connected to determine the widest range of circle shift to the right, links 403, 405 are adjusted to their shortest length while links 402, 404 are extended, lift arm 408 is rotated to substantially its furthest counter-clockwise position, as viewed by the operator, lift arm 409 is rotated through substantially 256° being aligned with links 403, 405, the wheels are tilted, the rear wheels are shifted to a position inside the cutting edge, and the 40 angle between the drawbars and the circle supporting frame is increased.

Fig. 33 illustrates another high-angle position of the blade with the machine on level ground, the adjusting mechanisms being positioned as 45 described in connection with Fig. 32 except that, because of the use of shorter center shift link 502A the full extent of movement of the lift arms is made effective in positioning the blade. Thus, in Fig. 33, the angle of the blade with the 50 axis of the wheel is 62° whereas in Fig. 32, discounting the 30° wheel tilt, the corresponding angle is 52°.

While the above described adjusting mechanisms are capable of adjusting the blade to a 55 high-angle cutting position when provided with manual controls, the provision of power-operated control mechanism not only makes for easier, more positive and quickly responsive adjustment, but also increases the range of high-angle cutting positions by several degrees. This is true 60 because, with power operation of the adjusting mechanisms, the spring compensating mechanisms heretofore necessary in high-angle cut machines are eliminated and no longer limit the 65 range of operation of the lift arms. Thus, while a center shift link of predetermined length affords a certain maximum high-angle position of the blade with manual controls, the maximum position with a center shift link of selected 70 length is increased by the provision of power-operated adjusting mechanisms.

It is to be noted that all of the various adjusting mechanisms either change the position of the line of draft, change the position of the blade with respect to the line of draft, or change the

position of the line of draft and the position of the blade with respect thereto at the same time. The line of draft is to be understood as the line passing through the intersection of the axes of pin 376 and bolt 374 (Fig. 9) and the center of 5 the circle.

I, therefore, claim as my invention:

1. In a road machine, a main frame having front and rear supports, a tool, a tool supporting frame, a pair of lift arms on said main frame, 10 lift links connecting said arms and said tool supporting frame, opposite housings mounted on said main frame, gearing in said housings for operating said arms, a power control mechanism having operative connections with said gearing, 15 each connection including a telescopic shaft extending forwardly from said power control mechanism and a shaft extending forwardly from the associated housing and adapted to be driven 20 from said telescopic shaft.

2. In a road machine, a main frame having front and rear supports, an auxiliary frame having a draft connection with said main frame, a tool, a tool supporting circle revolvably mounted in said auxiliary frame, means for shifting said auxiliary frame transversely with respect to said main frame including a rack slidably mounted on said main frame and connected to said auxiliary frame, gearing for sliding said rack, and a hollow 30 operating shaft for said gearing having a clutch element, means for revolving said circle on said auxiliary frame comprising a rack on said circle, gearing engaged with said rack, and operating means for said gearing including a shaft extending through said hollow shaft and having a second clutch element spaced from said first clutch element, a shiftable, revolvable sleeve having a third clutch element engageable with either said first or said second clutch element, power control mechanism including a lever for determining 35 forward or reverse rotation of said sleeve, and means for shifting said sleeve in either direction from a central neutral position including a peripheral rack on said sleeve, a pinion meshed therewith, and manually operable means for oscillating said pinion. 45

3. In a road machine, a main frame, a tool, a tool supporting frame, drawbars connected to said main frame and having aligned pivotal connections with said tool supporting frame, and 50 means for varying the angular relation of said tool supporting frame and said drawbars, comprising a housing mounted on said drawbars, a gear having a threaded hub, a screw pivoted to said tool supporting frame and having threaded 55 engagement with said hub, and means for rotating said gear comprising power control mechanism and connections therefrom to said gear.

4. In a road machine, a frame, wheels for supporting an end of said frame, means for tilting 60 said wheels with respect to said frame, means for shifting said wheels transversely with respect to said frame, power-operated control mechanism on said frame including a reversible clutch for selectively operating either of said means, and 65 means for connecting said clutch and said means including a housing on said frame, a first shaft mounted in said housing having a driving connection with said clutch and a first gear slidably and non-rotatably mounted thereon, a second 70 shaft mounted in said housing parallel to said first shaft having a second gear fixed therein, a third shaft mounted in said housing parallel to said first shaft having a third gear fixed thereon, said second and third gears being offset, and manu-

ally operable means for shifting said first gear into mesh with either of said last-named gears.

5. In a road machine, a frame, a tool, spaced lift members of adjustable length connecting said tool to said frame, means for moving said lift members to adjust said tool, a member mounted on said frame for laterally shiftable movement, and a link member connected between said laterally shiftable member and said tool and located 10 between said spaced lift members, said link member being a selected one of varying lengths to control the maximum high-angle cut of said tool.

6. In a road machine, a frame, a tool, spaced lift members of adjustable length connecting said tool to said frame, means for moving said lift members to adjust said tool, a member mounted on said frame between said lift members for laterally shiftable movement and having a plurality of fastening stations thereon, and a link member connected adjacent one end thereof at a selected one of said fastening stations and adjacent the opposite end thereof to said tool at a position adjacent the point of connection of a lift member with said tool, said link member being a selected one of varying lengths to control the maximum high-angle cut of said tool.

7. In a road machine, a frame, a wheel and axle assembly for supporting an end of said frame, means mounting said wheels on said axle for relative tilting movement, means connecting said frame and said axle for relative shifting movement, a housing on said frame, selective gear means in said housing, drive connections from said gear means to said mounting means 30 and said connecting means, and unitary selective control means for said gear means including an operating member and a control member for operatively connecting said operating member with either of said drive connections through said gear 35 means.

8. In a road machine, a frame, a tool adjustably mounted on said frame, means for adjusting said tool including opposite housings on said frame and gear means in said housings, and 40 power control mechanism for said tool having operative connections with said gear means, each connection including shafts extending forwardly from said mechanism and an associated housing, and a gear connection between the front ends 45 of said shafts.

9. In a grader; a main frame; an earth-engaging tool; spaced lift means connected to said tool; spaced gearing rearwardly of said tool at opposite sides of said main frame and connected 50 with said lift means; and means for driving said gearing comprising a source of power, a selective drive establishing member between said source of power and each gearing, a shaft extending forwardly from each drive establishing member, 55 and a second shaft extending forwardly from each gearing and connected adjacent its front with said first-mentioned shaft.

10. In a grader; a main frame; an earth-engaging tool; an operator's station on said main 60 frame and positioned rearwardly of said tool; spaced lift means connected to said tool; means for supporting said main frame on the ground including an adjustable wheel adjacent the rear of said main frame; spaced gearing rearwardly 65 of said tool at opposite sides of said main frame and connected with said lift means by shafting extending forwardly from said gearing; and means for driving said gearing and adjusting said wheel comprising a source of power, a selective drive establishing member between said 70

source of power and each gearing, another selective drive establishing member between said source of power and the wheel, each drive establishing member being adjacent said operator's station, a shaft extending forwardly from each of said drive establishing members associated with the gearing, a second shaft extending forwardly from each gearing and connected adjacent the front with the first-mentioned shaft, and an additional shaft extending rearwardly from said another drive establishing member for the adjustable wheel.

11. In a grader, a plurality of adjusting mechanisms, a source of power, and means for operating said adjusting mechanisms from said source of power including a plurality of selective drive establishing members, one of said drive establishing members being connectable with only one of said adjusting mechanisms, and another of said drive establishing members being connectable with more than one of said adjusting mechanisms, and control means for establishing a drive from said another drive establishing member to selected of said adjusting mechanisms connectable therewith.

12. In a grader, a main frame, an operator's station thereon, a source of power, drive establishing means adjacent said operator's station and connected to said source of power, said drive establishing means including a plurality of drive establishing members, a plurality of adjusting mechanisms, the number of said adjusting mechanisms being greater than the number of said drive establishing members, direct connections between one group of said adjusting mechanisms and a like number of said drive establishing members, and means for connecting another group of said adjusting mechanisms with another one of said drive establishing members including a control member for establishing a drive to a selected one of said another group of adjusting mechanisms, said control member being adjacent said operator's station for accessibility to an operator at said station.

13. In a grader, a main frame, an operator's station thereon, a source of power, drive establishing means adjacent said operator's station and connected to said source of power, said drive establishing means including a plurality of drive establishing members, a plurality of adjusting mechanisms, the number of said adjusting mechanisms being greater than the number of said drive establishing members, direct connections between one group of said adjusting mechanisms and a like number of said drive establishing members, means for connecting another group of said adjusting mechanisms with another one of said drive establishing members including a control member for establishing a drive to a selected one of said another group of adjusting mechanisms, and means for connecting a third group of said adjusting mechanisms with an additional one of said drive establishing members including a second control member for establishing a drive to a selected one of said third group of adjusting mechanisms, said control members being adjacent said operator's station for accessibility to an operator at said station.

14. In a grader; a main frame; an operator's station thereon; a source of power; an earth-engaging tool; adjusting mechanisms including spaced lift means connected to said tool to adjust the ends of said tool vertically; additional adjusting mechanisms for said tool; means for

supporting said main frame on the ground including a wheel; adjusting mechanisms for said wheel; and means operated from said source of power for selectively operating said lift means and said wheel adjusting mechanisms and said additional tool adjusting mechanisms comprising, drive establishing means adjacent said operator's station and connected with said source of power, said drive establishing means including a plurality of drive establishing members, a direct connection between one of said drive establishing members and one of said lift means, a direct connection between a second of said drive establishing members and a second of said lift means, means including a control member adjacent said operator's station for effecting a drive from a third of said drive establishing members to a selected one of said additional tool adjusting mechanisms, and means including a second control member adjacent said operator's station for selecting a drive from a fourth of said drive establishing members to a selected one of said wheel adjusting mechanisms.

15. In a grader; a main frame, an operator's station adjacent the rear of said main frame; a source of power; an earth-engaging tool positioned forwardly of said operator's station; adjusting mechanisms including spaced lift means connected to said tool to adjust the ends of said tool vertically; additional adjusting mechanisms for said tool; means for supporting said main frame on the ground including a wheel positioned adjacent the rear of said main frame; adjusting mechanisms for said wheel; and means operated from said source of power for selectively operating said lift means and said wheel adjusting mechanisms and said additional tool adjusting mechanisms comprising, drive establishing means adjacent said operator's station and connected with said source of power, said drive establishing means including a plurality of drive establishing members, a direct connection between one of said drive establishing members and one of said lift means, a direct connection between a second of said drive establishing members and a second of said lift means, means including a control member adjacent said operator's station for effecting a drive from a third of said drive establishing members to a selected one of said additional tool adjusting mechanisms, and means including a second con-

trol member adjacent said operator's station for selecting a drive from a fourth of said drive establishing members to a selected one of said wheel adjusting mechanisms, the drive from said drive establishing means to said lift means and said additional tool adjusting mechanisms including a plurality of shafts extending forwardly from said drive establishing means, and the drive from said drive establishing means to said wheel adjusting mechanisms including a shaft extending rearwardly from said drive establishing means. 5 10

16. In a grader; a main frame; means including a wheel and axle assembly for supporting said frame on the ground; means mounting said axle for relative shifting movement with respect to said frame; means mounting a wheel on said axle for relative tilting movement with respect to said axle; and means for selectively effecting relative tilting of said wheel or relative shifting of said axle comprising, a driving connection to said wheel, a driving connection to said axle, a driving member, and means including clutching mechanism having a single control member for selectively connecting said driving member with either one of said driving connections. 15 20 25

17. In a grader; a main frame having an operator's station adjacent the rear thereof; means including a wheel and axle assembly adjacent the rear of said frame for supporting said frame on the ground; means mounting said axle for relative shifting movement with respect to said frame; means mounting a wheel on said axle for relative tilting movement with respect to said axle; and means operable by an operator at said operator's station for selectively effecting relative tilting of said wheel or relative shifting of said axle in any relatively shifted positions of said axle and said wheel comprising, a driving connection to said wheel including telescopic shafting, a driving connection to said axle including telescopic shafting, a driving member supported by said frame and located adjacent said operator's station, and means including clutching mechanism having a single control member and supported by said frame adjacent said operator's station for selectively connecting said driving member with either of said telescopic shafting.

CARL A. GUSTAFSON. 59

CERTIFICATE OF CORRECTION.

Patent No. 2,189,344.

February 6, 1940.

CARL A. GUSTAFSON.

It is hereby certified that error appears in the printed specification of the above numbered patent requiring correction as follows: Page 2, first column, line 25, for "Figs. 27-28" read Figs. 27-30; page 3, second column, line 28, for the word "comprises" read comprise; page 4, first column, line 54, for "nut 235" read nut 253; page 7, first column, line 5, after "center" insert shift; page 9, second column, line 72, claim 4, for "therein" read thereon; page 11, first column, lines 28 and 29, claim 15, for "mens connected" read means connected; and that the said Letters Patent should be read with this correction therein that the same may conform to the record of the case in the Patent Office.

Signed and sealed this 16th day of April, A. D. 1940.
